(57) **CLAIM**

The ornamental design for a wipes dispenser opening, as shown and described.

DESCRIPTION

FIG. 1 is a perspective view of a wipes dispenser opening according to the invention;

FIG. 2 is a top view thereof;

FIG. 3 is a bottom view thereof;

FIG. 4 is a front side view thereof;

FIG. 5 is an back side view thereof;

FIG. 6 is a first side view thereof; and,

FIG. 7 is an opposite, second side view thereof.

The broken lines showing environmental structure are for illustrative purposes only and form no part of the claimed design.
